UNITED STATES PATENT OFFICE

2,677,381

SPRAY BLAST CLEANING CABINET

John L. Fisher, Harlingen, Tex., assignor to
 Spray-Blast Corporation of America, Harlin-
 gen, Tex., a corporation of Texas

Application May 25, 1950, Serial No. 164,150

1 Claim. (Cl. 134—56)

1

This invention comprises novel and useful im-
 provements in a spray blast cleaning cabinet and
 more specifically pertains to an apparatus espe-
 cially designed for expeditiously cleansing me-
 chanical parts of grease and the like.

The primary object of this invention is to pro-
 vide an apparatus to facilitate the degreasing
 and cleansing of machinery parts in a more thor-
 ough and expeditious manner.

A further object of the invention is to provide
 a cleansing apparatus in conformity with the
 preceding object which shall clean and reclaim
 for further use the cleansing fluid employed.

A still further object of the invention is to pro-
 vide a cleansing apparatus embodying a spray
 chamber and having a blower for discharging or
 venting vapor from the cabinet.

Yet another object of the invention is to pro-
 vide an improved cleansing apparatus which shall
 have a closure for the cleansing fluid tank to-
 gether with means for closing the tank to the
 interior of the device when the same is subjected
 to a dangerous temperature.

These, together with various ancillary objects
 and features of the invention, which will later
 become apparent as the following description
 proceeds, are attained by the present invention, a
 preferred embodiment of which has been illus-
 trated, by way of example only in the accom-
 panying drawings, wherein:

Figure 1 is a perspective view showing from the
 front a cleansing apparatus incorporating the
 principles of this invention;

Figure 2 is a vertical transverse sectional view
 through the cabinet of Figure 1, parts being
 broken away;

Figure 3 is a horizontal sectional view of the
 drip chamber of the cabinet, being taken substan-
 tially in the plane indicated by the section line
 3—3 of Figure 2;

Figure 4 is a vertical longitudinal sectional view
 through the cabinet taken substantially in the
 planes indicated by the broken section line 4—4
 of Figure 2;

Figure 5 is a vertical longitudinal sectional view
 taken upon an enlarged scale substantially upon
 the plane of section line 5—5 of Figure 3 and
 illustrating the construction of the resilient clos-
 ing means for the movable section of the cleans-
 ing fluid tank;

Figure 6 is a fragmentary vertical longitudinal
 sectional view taken substantially upon the plane
 indicated by the section line 6—6 of Figure 2;

Figure 7 is a fragmentary perspective view
 showing certain details of the blower, its driving
 motor and the mounting for the same;

2

Figure 8 is a view similar to Figure 5 but show-
 ing the movable cover of the cabinet in its closed
 position; and

Figure 9 is a fragmentary group assembly view
 in perspective showing a removable filter in ac-
 cordance with this invention and a supporting
 sleeve for the same.

Referring now more specifically to the accom-
 panying drawings, wherein like numerals design-
 ate similar parts throughout the various views,
 it will be seen that a cleansing apparatus incor-
 porating therein the principles of this invention
 is illustrated as including a cabinet or housing 10
 which may be economically constructed of light-
 weight sheet metal or any other suitable ma-
 terial, the same having a supporting grating 12
 extending horizontally across the interior thereof
 to divide the cabinet into an upper spray cham-
 ber 14 and a lower drip or drain chamber 16. The
 front of the spray chamber 14 is preferably open
 as shown in Figure 1, while a removable closure
 18 of any desired construction is provided for
 the front of the drain chamber 16.

The cabinet 10 includes a back wall 20 which
 upon its exterior surface is provided with a sup-
 porting bracket 22 upon which is mounted an
 electric motor or the like 24 provided with elec-
 trical connections not shown, by means of which
 the motor may be powered from any suitable
 electric source of power. Likewise secured to the
 back wall 20, upon the interior of the spray cham-
 ber 14, is a source of illumination such as an elec-
 tric light bulb and connection 26, provided with a
 suitable moisture proof transparent covering 28.
 The light is likewise provided with suitable con-
 nections not shown, to a suitable source of elec-
 tric power.

A curved deflecting baffle 30 is provided at the
 upper portion of the spray chamber 14, the same
 consisting of an arcuate sheet of metal or the
 like, having a flange 32 at its upper end whereby
 the baffle which extends across the entire width
 of the spray chamber may be secured to the back
 wall 20 at the uppermost portion thereof as shown
 clearly in Figure 4. The baffle curves from this
 upper portion of the back wall, forwardly and
 downwardly in the chamber 14 to about the mid-
 point of the same, the lower end of the baffle
 being inturned upon itself as at 34. The side
 edges of the baffle are of course secured to the
 side walls of the cabinet in any desired manner.
 An exhaust or vent pipe 36 extends through the
 upper portion of the baffle 30 and upwardly
 through the top of the cabinet structure, to pro-
 vide a vent or exhaust means for the spray cham-
 ber from the space below the upper part of the

baffle. A blower casing 38, see Figures 4 and 7, is provided, the same being mounted upon the interior surface of the back wall 20 in any desired manner, and this casing is provided with an inlet opening 40 which communicates with the interior of the spray chamber 14 beneath the baffle 30. An impeller in the form of a squirrel cage rotor or the like 42 of conventional design, is journaled in the casing 38 and connected with electric motor 24 for operation thereby. The casing has a discharge opening into which extends the lower end of the vent or exhaust pipe 36, the latter constituting the discharge for the blower.

The support grating 12 may consist of a reticulated screen of any desired character, the same being secured upon its marginal edges between upper and lower support bars 44 and 46 suitably attached to the cabinet 10. A drip basin 48 constitutes a collection means for the cleansing fluid sprayed into the interior of the spray chamber 14. This basin is preferably provided with a marginal flange 50 by means of which the same is secured to the lowermost clamping bar 46, the basin 48 thus underlying the support grating and extending across the entire area of the cabinet.

At a convenient position, the basin 48 is provided with a discharge or draining means, the same consisting of a depending sleeve 52, which is provided with outwardly extending pins or lugs 54. A detachable filter consisting of an annulus 56 having conventional bayonet slots 58 for releasably engaging the lugs or pins 54 is provided, the ring 56 having a basket 60 of reticulated or metal screen construction depending therefrom. This filter is removably secured to the collection basin 48 and serves to filter or strain the cleansing fluid collected by the basin before discharging the same downwardly into the drip or drain chamber.

Suitably positioned in the chamber 16 is a cleansing fluid tank 62 into which the drainage from the basin 48 is discharged. Positioned in the tank 62 below the point of discharge of the cleansing fluid from the basin 48 is a sediment tank 64 of any desired construction, and the same is preferably provided with a filtering screen 66 of any desired construction in its open upper end.

The tank 62 is open at its upper end, and the upper edges of the side walls of the same are flanged or bent inwardly as at 68 to provide upper guide surfaces.

A cover is provided for the tank 62, the same consisting of a stationary section 70, which is fixedly secured to the side walls and within the tank 62 but below the flanges 68, at one end of the tank, as for example to permanently close about one-half of the area of the tank. A movable section in the form of a panel 72 is provided, this movable section being slidably received upon the fixed section 70, when the movable section is in its open position. At its edges, the movable section is rolled upon itself as at 74 to provide tubular members. These tubular rolled portions 74 are provided with a closing wall 76 at one end, extending across the entire length of the movable section. Guide rods 78 provided with bolts 80 extend the length of the tank 62 below the flanges 68 and are secured to the end walls of the tank. Compression springs 82 encircle the guide rods 78 and abut against one of the end walls of the tank 62 and against the end wall 76 of the movable section to yieldingly urge this movable section towards its closed position. The movable section slides below and in guided engagement with the flanges 68 and slides upon the

top surface of the fixed section 70 and upon lower guideways 84. Figures 2 and 5 disclose the position of the movable section when the same is open against the bias of the spring 82 while Figure 8 shows the parts in a closed position of the movable section.

The forward ends of the movable and fixed sections are provided with depending lugs or hooks 86 and 88, which as shown in Figure 2 are adapted to be connected together as by a fusible link of any desired construction, indicated at 90.

It will thus be seen that the movable section is urged to its closed position to completely close the top of the cleaning fluid tank 62 to prevent communication of the same with the interior of the cabinet. However, the movable section is retained in open position by engagement of the fusible link 90 with the two hooks 86 and 88. When the temperature within the cabinet exceeds a safe value, as when a fire starts or the like, the fusible member 90 will melt thereby permitting the spring 82 to close the movable section of the cover.

As shown in Figure 4, a conduit 92 extends into the tank 62 adjacent the bottom of the same and constitutes an inlet for cleaning fluid, this pipe being connected as by a flexible conduit 94 with a feed hose 96. A second flexible hose 98 likewise extends through the front wall of the cabinet, this latter hose being connected on the interior of the cabinet with an air line 100 extending through the cabinet for supplying air under pressure from any suitable source to the device. The flexible hoses 96 and 98 are connected to a conventional form of spray nozzle 102 by means of which a blast of air from the hose 98 and air supply pipe 100 will cause the induction into the nozzle of cleansing fluid by means of the pipe 92, and conduits 94 and 96, whereby a spray of air and cleansing fluid may be manually directed into the interior of the spray chamber 14 for cleansing the parts or articles placed upon the supporting grill 12. The vapor rising from this spray will be prevented from escaping from the open front of the chamber 14, by means of the ventilating flow induced under the lower edge of baffle 30 by the blower assembly and discharged through the venting conduit 36. The condensate from the spray will drop down upon the grill 12, and be collected in the basin 48 therebeneath, and be strained by the filter 60 before dropping into the further filter 66 of the sediment tank 64 in the cleansing tank 62. After passing through these filters, the filtered cleansing fluid will then be recirculated through the spray nozzle as set forth hereinbefore.

From the foregoing, the construction and operation of the device together with its many advantages will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claim.

Having described the invention, what is claimed as new is:

A cleaning device comprising a cabinet having an open front, and upper and lower spray and drip chambers respectively, a blower for with-

drawing vapor from the upper end of said spray chamber, a cleansing fluid tank in said drip chamber, drain means between said chambers discharging liquid from said spray chamber into said tank, means for withdrawing cleaning fluid from said tank and spraying the same into said spray chamber, said tank having a cover comprising a fixed section covering a portion of the top of said tank and a sliding section, resilient means urging said sliding section to closed position, a fusible member connecting said sections and retaining said sliding section in open position.
